UNITED STATES PATENT OFFICE.

ULYSSES GRANT CAVE, OF LOUISVILLE, KENTUCKY.

MEMORANDUM AND RECORDING DEVICE FOR USE WITH TELEPHONES.

No. 879,082.

Specification of Letters Patent.

Patented Feb. 11, 1908.

Application filed June 3, 1907. Serial No. 877,008.

To all whom it may concern:

Be it known that I, ULYSSES GRANT CAVE, a citizen of the United States, resident of Louisville, in the county of Jefferson and State of Kentucky, have made a certain new and useful Invention in Memorandum and Recording Device for Use with Telephones; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a perspective view of the invention as applied to an ordinary desk telephone. Fig. 2 is a section on the line 2—2, Fig. 3. Fig. 3 is a plan view of the invention. Fig. 4 is a section on the line 4—4, Fig. 3. Fig. 5 is a sectional view of the invention as modified for use with a wall telephone, and with a single roll only. Fig. 6 is an end view of the invention as modified for use with a shelf telephone. Fig. 7 is a side view of a modified form of the invention, having supporting legs. Fig. 8 is a detail perspective view, of the removable plate designed to receive the supporting rods and the angle bar support. Fig. 9 is a detail perspective view of one of the pivoted clamps. Fig. 10 is a detail fragmentary sectional view showing the knob tension. Fig. 11 is a detail perspective view of one of the knob extensions.

The invention has relation to memorandum devices for use with telephones, having for its object to provide recording means in connection with the memorandum device, together with simple operating mechanism. Other objects and advantages will herein-after appear.

With this object in view the invention consists in the novel construction and combinations of parts as hereinafter set forth.

In the accompanying drawings illustrating the invention the letter *a*, designates a supporting frame consisting of a cover or platform plate *b*, having side frame plates *c*, secured thereto, such side frame plates having enlargements *d*, at each end of general circular or polygonal form, the enlargements at the upper raised or rear end, extending above and below the side frame bars and the en-

largements at the lower or forward end extending below the side frame bars, the platform plate having an upward cover extension *e*, at its rear or upper end for the paper roll and its shaft at this end, and a downward cover or guard extension *f*, at its forward or lower end for the paper roll and its shaft at this end acting as a connection for such enlargements and for the side frame plates and forming covered spaces wherein the paper rolls may be located. The shafts for the paper rolls have journal bearings in the end enlargements *d*, of the side frame plates, the rear shaft being located in line with the side frame bars and the forward shaft below the same, such shafts carrying the paper rolls *g*, *g'*, located below and hidden by the end extensions of the platform plate.

Paper from the supply roll *b*, at the upper end of the device passes through slot *h*, located in the angle between the platform plate and its upward extension, thence along the top of the platform plate and down through slot *h'* in the lower end of the same to the record roll *b'*. The paper upon these rolls *b*, *b'*, is rolled thereon, as shown, in strips of two plies or layers, the lower duplicate strip passing down upon one side of the lower paper roll, but not being rolled thereon, the end of this lower strip being designed to be torn off for use. The upper or record strip is wound upon the lower roll and provides a permanent record of transactions. Tension springs *j*, are provided for pressure against both paper rolls, the coiled ends of these springs being preferably wound around brace rods *j'*, having their ends secured to the side frame plates below and hidden by the platform plate. The side frame plates have lateral inward extending guide lugs *k*, at intervals, under which the paper from the rolls passes. A carbon sheet *v*, is located between the two layers of paper upon the platform plate, this sheet extending transversely across such plate and passing at its ends down in the narrow space *v'*, between the side frame plates and the platform plate at each side, a clamp *m*, being provided at each side to secure such ends in place. This clamp *m*, is pivoted to a side frame plate at one end, and has parallel side bars *m'* designed to be pressed down into close engagement with the upper edge portion of such side frame

plate, which is received between the parallel bars of the clamp. The inner side wall of the grooved clamp is thus located in the narrow interval between the side frame plate and platform plate, and acts to clamp in a secure manner the end of the carbon sheet.

Each paper roll shaft is usually provided with an operating knob extension n , at one side, this knob extension being shown in the present case as having a bifurcated stem n' , designed to pass within the hollow end of the shaft into engagement with a transverse pin n^2 , whereby, when the knob is turned, the shaft will turn therewith, and at the same time the knob can be readily removed when the shaft of the paper roll, which has bearings in perforation of the enlargement of the side frame bars, with the roll carried thereby, can also be removed. This paper roll is then slipped off from the shaft for filing of record and a new roll having been slipped in place upon the shaft, it is replaced in the machine.

The middle portion of the platform plate at each side as shown in Fig. 5 is bent inward upon itself to form guide grooves p , below the plate, in which a removable plate b , is provided, having its forward and rear ends bent into cylindrical form at q' . In these cylinder extensions q' , are received transverse supporting rods r, r , connecting the two ends of spring clamp s , designed to be slipped upon the standard of a desk telephone, an adjusting screw r' , being provided for such clamp.

In case the device is used with a wall telephone, a longitudinal seat or socket strip q^2 , is secured centrally to the plate q , in which the end portion of an angle bar support t , is secured and held by adjusting screw t' , as shown in Fig. 5 of the drawings. This angle bar support has a downward bent end t^2 , received and held in a socket of a wall plate t^3 .

In Fig. 6 of the drawings, the transverse supporting rods r, r , are shown as connected by a clamp plate u , having an opening therein to receive the edge portion of a shelf when the device is used in connection with a shelf telephone, a clamping screw u' being provided.

In Fig. 7 of the drawings a further modified form of support for the invention is shown, w, w , representing supporting legs having pivotal connection with the side frame plates at w' , and having stop engagement at w^2 with the rear paper roll shaft, and at w^3 with an inturned lug of the side frame plate. These legs w, w , are each formed of a single piece of wire, as shown and are designed to be capable of being folded inward out of the way, as shown in dotted lines in such figure, when the device may be readily slipped into the pocket.

The rear or upper extension e , of the platform plate may have guideways e' , at each

side as shown in Fig. 5 of the drawings, 65 wherein an index call card for frequent calls may have place, or wherein a writing pad may be located and used for memorandums when the device is otherwise being used for duplicate orders.

In Fig. 5 of the drawings is shown a modified form of the invention, in which but one paper roll is shown located at the upper end of the frame. In this case, the original and duplicate paper strips pass from the roll 75 down over the platform and through the slot h' , at the lower end of the frame the ends of such strips hanging loosely in position to be torn off.

Having thus described the invention, what 80 I claim and desire to secure by Letters Patent is—

1. In a device of the class described, a frame provided with a platform plate, side frame bars separated from said platform 85 plate by an interval at each side, and having end enlargements, rotary shafts having seats in the end enlargements of said side frame bars, each such shaft having a hollow end portion provided with a transverse pin and a 90 removable handle knob having a bifurcated stem engaging said pin, and carbon sheet clamp devices hinged to the side frame bars and having parallel bars embracing said side frame bars and extending in the intervals 95 between the platform plate and side frame bars.

2. In a device of the class described, a frame provided with a platform plate, side frame bars separated from said platform 100 plate by an interval at each side, and having end enlargements, rotary shafts having seats in the end enlargements of said side frame bars, each such shaft having a hollow end portion provided with a transverse pin and a 105 removable handle knob having a bifurcated stem engaging said pin, and carbon sheet clamp devices hinged to the side frame bars and having parallel bars embracing said side frame bars and extending in the intervals 110 between the platform plate and side frame bars, said frame having transverse tubular seats below the same and a supporting clamp device having transverse bars engaging such tubular seats.

3. In a device of the class described, a frame provided with a platform plate, side frame bars separated from said platform plate by an interval at each side, and having end enlargements extending at one end of the frame 120 above and below the platform plate and at the other end of the frame below the platform plate, rotary shafts having seats in said end enlargements and located one in line with the side frame bars and the other below the 125 same, each such shaft having a hollow end provided with a transverse pin and a removable handle knob having a bifurcated stem

engaging such pin, said platform plate having a slot at each end portion thereof, an upward projecting cover extension at one end overlying the rotary shaft at such end 5 and a downward projecting guard extension at the other end for the rotary shaft at such end, and carbon sheet clamp devices having parallel side bars extending in the intervals

between the platform plate and side frame bars.

In testimony whereof I affix my signature, in presence of two witnesses.

ULYSSES GRANT CAVE.
